UNITED STATES PATENT OFFICE

108,387

DESIGN FOR A COAT

Max Bagedonow, New York, N. Y.

Application December 28, 1937, Serial No. 73,909

Term of patent 3½ years

To all whom it may concern:

Be it known that I, Max Bagedonow, a citizen of the United States and residing in Manhattan, in the city, county, and State of New York, have invented a new, original, and ornamental Design for a Coat, of which the following is a specification, reference being had to the accompanying drawing, forming part thereof.

Fig. 1 is a front view of a coat showing my new design.

Fig. 2 is a rear view thereof.

The tucks on the back of the sleeves are longer than those on the front.

I claim:

The ornamental design for a coat substantially as shown and described.

MAX BAGEDONOW.
